UNITED STATES PATENT OFFICE.

CHARLES WHITE, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,386,747.

Specification of Letters Patent. Patented Aug. 9, 1921.

Application filed July 11, 1918. Serial No. 244,360.

To all whom it may concern:

Be it known that I, CHARLES WHITE, a citizen of the United States, residing at East Orange, in the county of Essex, State 5 of New Jersey, have invented certain new and useful Improvements in Telephone-Exchange Systems, of which the following is a full, clear, concise, and exact description.

This invention relates to telephone 10 exchange systems and more particularly to such systems in which trunk circuits are employed.

In systems of this nature in which the same trunk circuit is employed for different 15 classes of service, it is desirable to provide signaling means to positively indicate the class of service with which the trunk circuit is to be associated in a particular instance.

It is the object of the present invention to 20 provide an improved system of this character which is simple and inexpensive and provides signaling means for certain classes of service which are unaffected by the operation of the signaling means for the other 25 classes of service or by incidental features encountered in the operation of the system.

To attain this object in accordance with a 30 feature of this invention, a trunk circuit arranged for plural service and reciprocal operation and provided with two signal control means responsive to signaling currents of different characteristics is provided with means responsive to the operation of one of the signal control means for rendering the 35 other ineffective while the trunk is being used for the selected service.

In accordance with another feature of the 40 invention, such a trunk circuit is provided with means also responsive to the operation of the selected signal control means to discharge the capacitance retained in the trunk circuit after the selected signaling current has been removed, thereby preventing the 45 false operation of the other signal control means when it is associated with the trunk circuit upon the disengagement of the trunk circuit.

These and other features not specifically 50 mentioned above will more fully appear from the following specification and the annexed drawing, in which the figure shows diagrammatically a trunk circuit embodying the invention, together with sufficient portions of suitable connecting circuits for the

different classes of service to properly illustrate the invention. 55

In the drawings the switchboards, operators' positions or stations X and Y are joined by the trunk circuit A terminating at position X in jacks 2 and 14 and at position 60 Y in jacks 102 and 114. Associated with jacks 2 and 14 are calling signal lamps 18 and 26 respectively and associated with jacks 102 and 114 are calling signal lamps 118 and 126 respectively. Jacks 2 and 102 65 are adapted for use in connection with one class of service such as local calls, while jacks 14 and 114 are adapted for use in connection with another class of service such as toll calls. At station X suitable connecting 70 circuits B and C are provided for use with jacks 2 and 14 respectively and at station Y similar connecting circuits D and E are provided for use with jacks 102 and 114 respectively, only sufficient portions of each connecting circuit being shown to properly 75 illustrate the invention.

It is believed that the invention may be more fully comprehended from the following 80 description of the operation of the embodiment shown on the drawing.

Assuming that it is desired to extend a local connection from position X to position Y, the operator at position X inserts the calling plug 1 of link circuit B into the jack 85 2 of the trunk circuit A. Supervisory lamp 4 is lighted and relay 7 is operated over a circuit established from battery through lamp 4, resistance 3, sleeve contacts of plug 1 and jack 2, lower normal contact of relay 90 8, lower normal contact of relay 9 and winding of relay 7 to ground. The closure of the upper contact of relay 7 short-circuits the left-hand high resistance winding of relay 10, while the closure of the lower contact 95 of relay 7 causes the operation of relay 11 over a circuit extending from battery through the winding of relay 11, the lower normal contact of relay 12, the upper normal contact of relay 13 and the lower contact of relay 7 to ground. Relay 11 is thereupon locked over a circuit extending from battery, through the winding and lower outer alternate contact of relay 11 and the lower contact of relay 7 to ground. Relay 13 is also 105 operated over a circuit extending from battery through the upper winding of relay 13, the upper outer alternate contact of relay

11, and the lower contact of relay 7 to ground. Relay 13 is thereupon locked over a circuit extending from battery, through the upper winding and middle alternate contact of relay 13, and the lower contact of relay 7 to ground. By the closure of the upper alternate contact of relay 13, a busy test potential is connected to the sleeve contact of jack 14 through resistance 15 and the upper alternate contact of relay 13. The operation of relay 11 operates relay 110 at position Y over a circuit extending from battery, through resistance 16, the upper inner alternate contact of relay 11, the upper contact of relay 7, the left-hand low resistance winding of relay 10, the upper normal contact of relay 9, the middle normal contact of relay 8, the ring conductor of the trunk circuit, the middle normal contact of relay 108, the upper normal contact of relay 109, both windings of relay 110 in series, the upper and lower normal contacts of relay 111, the upper normal contact of relay 108, the tip conductor of the trunk circuit and the lower inner alternate contact of relay 11 to ground. Relay 10 does not receive sufficient current to cause its operation at this time, but relay 110 is operated, effecting the operation of relay 112 over a circuit extending from battery, through the winding of relay 112 and the contact of relay 110 to ground. By the closure of its upper outer alternate contact, relay 112 extends the continuity of the conductor associated with the ring contact of jack 102, while by the closure of its upper inner alternate contact lamp 118 is lighted over a circuit extending from battery, through the lower normal contact of relay 113, the upper inner alternate contact of relay 112 and the lamp 118 to ground. The closure of the lower outer alternate contact of relay 112 connects a busy test potential to the sleeve contact of jack 114 through resistance 115, and the lower alternate contact of relay 112.

The operator at station Y observing the illumination of lamp 118 inserts plug 101 of link circuit D into the jack 102, thereby operating supervisory relay 106 over a circuit extending from battery, through the winding of relay 106, the ring contacts of plug 101 and jack 102, the upper outer alternate contact of relay 112, resistance 119 and the tip contacts of jack 102 and plug 101 to ground. Supervisory lamp 104 is thereupon shunted by the resistance 105 and therefore is not lighted. Relay 107 is operated over a circuit extending from battery, through the contact of relay 106, resistance 105 and 103, the sleeve contacts of plug 101 and jack 102, the lower normal contact of relay 108, the lower normal contact of relay 109, and the winding of relay 107 to ground. The closure of the upper contact of relay 107 short-circuits the left-hand high resist-

ance winding of relay 110, thereby reducing the resistance in circuit with the right-hand low resistance winding of relay 10 sufficiently to permit its operation at this time. Upon the actuation of relay 107, relay 113 is operated over a circuit extending from battery, through the upper winding of relay 113, the lower inner alternate contact of relay 112, the upper normal contact of relay 113 and the lower contact of relay 107 to ground. The opening of the lower normal contact of relay 113 extinguishes the lamp 118, and the closure of the lower alternate contact of relay 113 completes a locking circuit, therefor, extending from battery, through the lower winding of relay 113 and the contact of relay 110 to ground.

The operation of relay 10 responsive to the short-circuiting of the high resistance winding of relay 110 causes the operation of relay 12 over a circuit extending from battery, through the winding of relay 12 and the contact of relay 10 to ground and locks relay 13 over a circuit extending from battery, through the lower alternate contact and lower winding of relay 13 and the contact of relay 10 to ground. Lamp 18 is not lighted due to the opening of the lower normal contact of relay 13. In operating, relay 12 extends the continuity of the conductor connected to the ring contact of jack 2, thereby operating supervisory relay 6 over a circuit extending from battery, through the winding of relay 6, the ring contacts of plug 1 and jack 2, the upper outer alternate contact of relay 12, resistance 19 and the tip contacts of jack 2 and plug 1 to ground. Lamp 4 is thereupon shunted by the resistance 5 and thereby extinguished, notifying the operator at position X that the operator at position Y has answered the call. A talking circuit is thereupon completed over the conductors of the trunk circuit so that a subscriber whose line is associated with link circuit B at position X may converse with another subscriber whose line is associated with link circuit D at station Y.

Upon the completion of the conversation, the operator at position X removes the plug 1 from the jack 2, releasing relay 7 to remove the short circuit around the left hand high resistance winding of relay 10 and thereby increasing the resistance in circuit with relay 110 sufficiently to cause its release. Relay 112 thereupon releases to open the conductor connected to the ring contact of jack 102 causing the release of relay 106, which removes the resistance 105 from its shunt relation with lamp 104 and causes the lighting of such lamp over a circuit extending from battery, through lamp 104, resistance 103, the sleeve contacts of plug 101 and jack 102, the lower normal contact of relay 108, the lower normal contact of relay 109, and the winding of relay 107 to ground. Upon the subsequent

disconnection of link circuit D, all apparatus returns to normal.

In case the local call originates at position Y, upon the insertion of the plug 101 into the jack 102, supervisory lamp 104 is lighted, relays 107, 111, 113, 10 and 12 are operated, relay 113 is locked, calling signal lamp 18 is lighted, a busy potential is connected to the sleeve contacts of jacks 114 and 14 and the break in the ring conductor is closed as previously described in connection with lamps 4 and 118, relays 7, 11, 13, 110 and 112, and jacks 14 and 114. Upon the insertion of plug 1 into the jack 2, in answering the call, relays 106, 107, 110, 13 are operated, relay 13 is locked, lamp 104 is shunted by resistance 105 and thereby extinguished, lamp 18 is extinguished, a break in the ring conductor associated with jack 102 is closed to complete the circuit for relay 106, including resistance 119 as previously described for relays 107, 10, 113 and 6, lamps 4 and 118, resistances 5 and 19 and jack 2. Upon the disconnection of the plug 101 from the jack 102, relays 107, 10, 12 and 6 release, the break and the ring conductor associated with jack 2 is opened, the resistance 5 is removed from its shunt relation with the lamp 4, which is thereby lighted, as previously described for relays 7, 110, 112 and 106, jack 102, resistance 105 and lamp 104. Upon the subsequent disconnection of plug 1 from jack 2 all apparatus returns to normal.

In case it is desired to extend a toll call from position X to position Y, the operator at position X inserts the plug 20 of a link circuit C into the jack 14, thereby operating relay 22 over a circuit extending from battery, through resistance 21, the sleeve contacts of plug 20 and jack 14, and the winding of relay 22 to ground. Relay 8 is thereby operated over a circuit established from battery, through the lower normal contact of relay 13, the upper normal contact of relay 12, the winding of relay 8 and the alternate contact of relay 22 to ground. By opening its upper and middle normal contacts relay 8 removes the tip and ring conductors of the trunk circuit from their normal association with the local jack 2 and by closing its upper outer and lower inner alternate contacts connects such conductors to the tip and ring contacts respectively of the toll jack 14. A busy test potential is also connected to the sleeve contact of jack 2, through resistance 15 and the upper inner alternate contact of relay 8. The operator at position X actuates the ringing key 24 to connect a source of signaling current to the trunk circuit, thereby operating relay 123 over a circuit extending from the source of signaling current, through the lower alternate contact of ringing key 24, the ring contacts of plug 20 and jack 14, the lower inner alternate contact of relay 8, the ring conductor of the trunk cir-

cuit, the middle normal contact of relay 108, the condenser 125, the winding of relay 123, the upper normal contact of relay 108, the tip conductor of the trunk circuit, the upper alternate contact of relay 8, the tip contacts 70 of jack 14 and plug 20 and the upper alternate contact of ringing key 24 to ground. Relay 109 is thereupon operated over a circuit established from battery, through the lower normal contact of relay 113, the upper 75 normal contact of relay 112, the contact of relay 123, the winding of relay 109 and the normal contact of relay 122 to ground. Relay 109 thereupon locks over a circuit extending from battery, through the lower normal contact of relay 113, the upper normal contact of relay 112, the middle alternate contact and winding of relay 109 and the normal contact of relay 122 to ground. 80 Lamp 126 is lighted over a circuit extending from battery, through the lower normal contact of relay 113, the upper normal contact of relay 112, the middle alternate contact of relay 109, and the lamp 126 to ground. A busy test potential is also connected to the 85 sleeve contact of jack 102 through resistance 115, the lower alternate contact of relay 109 and the lower normal contact of relay 108. By the opening of the upper normal contact of relay 109, the left-hand winding 90 of relay 110 is disconnected from its normal association with the ring conductor of the trunk circuit and the slow operating relay 110 is thereby rendered unresponsive during 95 the continued operation of relay 109. The 100 closure of the upper alternate contact of relay 109 forms a shunt path through resistance 127 and the upper alternate contact of relay 109, around condenser 128, serving to discharge the residual charge retained by 105 such condenser from the application of the signaling current.

In answering the call, the operator at position Y inserts the plug 120 of the link circuit E into the jack 114, thereby operating 110 relay 122 over a circuit extending from battery, through resistance 121, sleeve contacts of plug 120 and jack 114 and the winding of relay 122 to ground. Relay 109 is released, extinguishing the lamp 126. Relay 115 108 is thereupon operated over a circuit from battery, through the lower normal contact of relay 113, the upper normal contact of relay 112, the winding of relay 108 and the alternate contact of relay 122 to 120 ground. The opening of the upper and middle normal contacts of relay 108 removes the tip and ring conductors respectively of the trunk circuit from their normal association with the tip and ring contacts of 125 jack 102, while the closure of the upper and lower alternate contacts of relay 108 connects such conductors to the tip and ring conductors respectively of jack 114. The closure of the middle alternate contact of 130

relay 108 serves to maintain a busy test potential connected to the sleeve contact of jack 102 through resistance 115 and the middle alternate contact of relay 108. As 5 in the former case, a talking circuit is there-
upon completed over the conductors of the trunk circuit so that a subscriber whose line 10 is associated with link circuit C at position X may converse with another subscriber 15 whose line is associated with the link circuit E at position Y.

Upon the termination of the conversation, 20 the operator at position X actuates the ringing key 24, operating supervisory relay 129 over a circuit formed from the source of 25 signaling current through the lower alternate contact of key 24, the ring contacts of plug 20 and jack 14, the lower alternate contact of relay 8, the ring conductor of the 30 trunk circuit, the lower alternate contact of relay 108, the ring contacts of jack 114 and plug 120, the lower normal contact of key 124, the winding of relay 129, the upper normal contact of key 124, the tip contacts 35 of plug 120 and jack 114, the upper alternate contact of relay 108, the tip conductor of the trunk circuit, the upper alternate contact of relay 8, the tip contacts of jack 14 and plug 20 and the upper alternate contact of key 24 to ground. Supervisory lamp 40 130 is thereby lighted over a circuit extending from battery, through the lamp 130 and the contact of relay 129 to ground. In response to the illumination of the lamp 130, 45 the operator at position Y removes the plug 120 from the jack 114 and the operator at position X also removes the plug 20 from the jack 14, thereby permitting all apparatus to return to normal.

40 In case the toll call is originated at position Y, the insertion of the plug 120 into the jack 114 causes the operation of relays 122 and 108 over circuits similar to those described for relays 22 and 8, thereby re- 45 moving the trunk conductors from their normal association with jack 102 and placing the busy test potential on the sleeve contact of such jack in a manner similar to that previously described in connection with 50 jack 2. Upon the actuation of ringing key 124, relay 23 is operated, causing the subsequent operation and locking of relay 9, the removal of relay 10 from its association with the ring conductor of the trunk circuit, the discharge of condenser 28 through 55 a shunt path including the resistance 27 and the lighting of lamp 26 as previously described for relays 123, 109, 110, condenser 128, resistance 127 and lamp 126. In an- 60 swering the call, the insertion of plug 20 into jack 14 causes the operation of relays 22 and 8, thereby removing the trunk conductors from their normal association with jack 2, maintaining a busy test potential 65 connected to the sleeve of such jack, releas-

ing relay 9 and extinguishing lamp 26, as previously described in connection with relays 122, 108, and 109, jack 102 and lamp 126. A talking circuit is also established similar to that of the preceding case, enabling the subscribers whose lines are associated with the link circuits C and E respectively to converse. Upon the completion of the conversation the operator at position Y actuates the ringing key 124, thereby operating relay 29 and lighting lamp 30 as previously described in connection with key 24, relay 129 and lamp 130. Upon the subsequent disconnection of both link circuits from the trunk circuit all apparatus 70 returns to normal.

75 It will be evident that upon the operation of relay 23 or 123 in response to a toll call, not only is the corresponding slow operating relay 10 or 110 provided with the local 80 service removed from its effective association with the trunk circuit, thereby preventing interference between the signaling control means for the different classes of service, but also the residual charge retained by 85 the associated condenser 28 or 128 is discharged through a shunt path, so that it does not produce a false operation of the relay 10 or 110 when such relay is reconnected through the trunk circuit upon the discon- 90 nection of the toll link circuit from the trunk circuit. The relays 10 and 110 are made slow to operate to insure the operation of relays 23 and 9 or relays 123 and 109 prior to the operation of such slow op- 95 erating relays.

100 What is claimed is:

1. In a telephone exchange system, a plural service trunk circuit for reciprocal operation between two stations, signal control means at each station for each service, said means for different services being responsive to signaling currents of different characteristics, means at each station for selectively impressing currents of different 105 characteristics on the trunk circuit to operate the associated signal control means at the other station, and means operating upon the response of one signal control means to render the other signal control means at the 110 same station unresponsive.

115 2. In a telephone exchange system, a plural service trunk circuit interconnecting two stations, signal control means at one station for each service, said means being responsive to signaling currents of different characteristics, means at the other station for selectively impressing currents of different characteristics on the trunk circuit, a capacitance device at the first mentioned 120 station receiving a charge during the impression of the signaling current of one characteristic, and means controlled by the response of the associated signal control means to discharge the residual charge re- 125 130

tained by the device after the cessation of such impression.

3. In a telephone exchange system, a plural service trunk circuit for reciprocal operation between two stations, signal control means at each station for each service, said means for the different services being responsive to signaling currents of different characteristics, means at each station for selectively impressing currents of different characteristics on the trunk circuit to operate the associated signal control means at the other station, a capacitance device at each station receiving a charge during the impression of the signaling current of one characteristic at the other station, and means controlled by the response of the associated signal control means to discharge the residual charge retained by the device upon the cessation of such impression.

4. In a telephone exchange system, a plural service trunk circuit interconnecting two stations, signal control means at one station for each service, said means being responsive to signaling currents of different characteristics, means at the other station for selectively impressing currents of different characteristics on the trunk circuit, a capacitance device at the first mentioned station receiving a charge during the impression of signaling current of one characteristic, and means operating upon the response of the associated signal control means to simultaneously render the other signal control means unresponsive and to discharge the residual charge retained by the device after the cessation of such impression.

In witness whereof, I hereunto subscribe my name this 2nd day of July, A. D. 1918.

CHARLES WHITE.
